UNITED STATES PATENT OFFICE.

LEGER S. CASTONGUAY, OF AKRON, OHIO, ASSIGNOR TO THE WILLIAMS FOUNDRY
AND MACHINE COMPANY, OF AKRON, OHIO, A CORPORATION OF OHIO.

VULCANIZER.

Application filed October 30, 1925. Serial No. 65,780.

To all whom it may concern:

Be it known that I, LEGER S. CASTONGUAY, a citizen of the United States of America, and a resident of Akron, in the county of 5 Summit and State of Ohio, have invented certain new and useful Improvements in Vulcanizers, of which the following is a full, clear, and exact description.

My invention relates to watch case vulcanizers, and the principal object of my invention is to provide a new and improved vulcanizer of this type. In the drawings accompanying this specification and forming a part thereof I have shown, for purposes 10 of illustration, one form which my invention may assume. In these drawings:

Figure 1 is a front elevation of this illustrative embodiment of my invention,

Figure 2 is a section on the line 2—2 of 20 Figure 1, while

Figure 3 is a side elevation of this illustrative embodiment of my invention.

The vulcanizer herein shown comprises a pair of stationary mold sections 11; each provided with a pair of legs 12 arranged to be secured by means of bolts 13 to a common supporting pedestal 14. These stationary mold sections 11 are further secured together by means of four lugs 15 which extend outwardly from each of the stationary mold sections 11, two on each side of each section one above the other, and which are themselves secured together by means of bolts 16 which also secure to each pair of upper lugs 25 an upper supporting bracket 17 and to each pair of lower lugs a lower supporting bracket 18 positioned directly beneath the corresponding upper supporting bracket 17 and cooperating with the corresponding upper 30 supporting bracket 17 to support two bearing shafts 19 and 20 each held against rotation in its supporting brackets 17 and 18 by means of suitable set screws 21.

Pivottally mounted on each of the shafts 45 19, by means of an upper bearing 22 engaging the shaft 19 above the upper supporting bracket 17, and a lower bearing 23 engaging the shaft 19 below the lower supporting bracket 18, is a movable mold section 50 24 arranged to cooperate with the corresponding stationary mold section 11 to form the desired cavity 25, and to support any additional part such as the bull ring 26 ordinarily employed when the mold is used

for curing a pneumatic tire, and held at the 55 proper elevation by means of a machine screw 27 adjustably mounted in the upper bearing 22 with its tip engaging the upper end of the shaft 19.

The outer faces of the movable mold section 24 may be provided with suitable pockets 28 for the reception of heat insulated material intended to decrease the radiation of heat from the mold, and these pockets may be closed by suitable plates 50, and the entire exterior periphery of the mold may also be covered with similar heat insulated material to decrease such radiation from that surface.

Mounted on each of the shafts 20 by means 70 of a tongue 29 is a link 30 supporting in its forks 31 a bearing shaft 32, and mounted on each of these bearing shafts 32 is a bar 33 extending across the face of the corresponding movable mold member 24, connected by means of a pin 34 to a spider 35 provided with an annular bearing surface 36 engaging the corresponding movable member 24 along the entire circumference of the mold member 24, additionally supporting the spider 35 by means of lugs 37 carried on the spider 35 and resting on the upper face of the bar 33, engaging the spider 35 by means of cylindrical surfaces 38 on the bar 33 contacting with cooperating cylindrical surfaces 39 on the spider 35 to permit swiveling of the spider 35 relative to the bar 33 about an axis parallel to the shafts 19, and drawn and held in position, with the spider 35 holding the movable mold section 24 tightly against the cooperating stationary mold section 11, by means of a bolt 40 engaging in the slot 41 in the free end of the arm 33 and screw threaded into a nut 42 pivoted on the corresponding shaft 19 between its upper and lower supporting brackets 17 and 18.

Mounted upon each of the bars 33, in a recess 43 adjacent the bar supporting shaft 32, is a hook member 44 pivoted to the bar 33 at 45, and acted upon by means of a compression spring 46 to maintain the hook 47 constantly biased toward a lug 48 carried by the corresponding movable mold section 24, and thus in position to engage the lug 48 and crack the mold when the bar 33 is swung about its pivot 32.

In order to prevent radiation of heat from

the inner periphery of the molds I form the spiders 35 solid to thus act as closures for the central apertures in the outer faces of the movable molds. And to prevent escape 5 of the heat from one of the molds when the other mold is open, I interpose, at the junction of the two stationary mold sections 11, a barrier 49 formed of any suitable material such as sheet steel or cast iron.

10 In operation, the article to be cured is placed within the cavity of one of the stationary mold sections 11, the corresponding movable mold section 24 is swung into position, the bar 33 is rotated to bring the spider 15 35 against the outer face of the corresponding movable mold section 24, and the bolt 40 is swung into position within the slot 41 in the free end of the bar 33 and rotated to cause the bar 33 to act through the spider 35 20 to firmly seat the movable mold section 24 against the stationary mold section 11, the necessary adjustment between the bar 33 and the spider 35 occurring by slippage of the spider 35 on the bar 33 at the cylindrical 25 bearing surfaces 38 and 39, and by translatory movement of the entire bar 33 about the pivots 19 and 20 of the nut 42 and link 30, and the spider 35 serving to seal the central opening in the outer face of the movable 30 mold section 34 and, because of the presence of the plate 49, to close the space within the corresponding mold regardless of the condition or position of the movable mold member 11. And on opening the mold the bar 33, 35 after sufficient movement to attain considerable momentum, will suddenly bring the hook 47 into engagement with the lug 48 to readily break the movable mold section 24 from the corresponding stationary mold section 11, after which the bar 33 will continue to open the movable mold section 24 until the hook 47 slips from the lug 48.

From the above description it will be obvious to those skilled in the art that the embodiment of my invention herein disclosed provides a watch case heater accomplishing the objects of my invention and superior particularly in the method of clamping the movable section in position on the corresponding stationary mold section, the method of breaking the mold, and the segregation of the space within the mold to prevent radiation of heat from the inner periphery of the mold. It will also be apparent to those skilled in the art that the embodiment of my invention herein disclosed embodies advantages other than those specifically pointed out or suggested herein, and also that this particular embodiment of my invention may be various changed and modified without departing from the spirit of my invention or sacrificing the advantages thereof. It will therefore be understood that this disclosure is illustrative only and 65 that my invention is not limited thereto.

I claim:

1. A watch case vulcanizer comprising a pivotally supported movable mold section; and mechanism for holding said movable section in position against a cooperating mold section comprising, a spider having its outer engaging surface arranged to bear against said movable section, and a member pivotally supported for movement about an axis parallel to the pivot supporting said movable section, and arranged to engage said spider over cooperating surfaces on said spider and said member formed to permit relative movement of said spider and said member about an axis also parallel to said pivot.

2. A watch case vulcanizer comprising a pivotally supported movable mold section; mechanism for holding said movable section in position against a cooperating mold section comprising a pivotally supported bar; and means on said bar and said movable section formed to inter-engage upon outward movement of said bar to cause such movement to break said movable section from 80 said cooperating section.

3. A watch case vulcanizer comprising a plurality of aligned annular mold sections, and means arranged to close the central openings in the remote faces of the two end sections. 95

4. A watch case vulcanizer comprising a pivotally supported movable annular mold section; and mechanism for holding said movable section in position against a cooperating mold section comprising, a spider having its outer engaging surface arranged to bear against said movable section along the entire circumference thereof, and a member pivotally supported for movement about an axis parallel to the pivot supporting said movable section, and arranged to engage said spider over cooperating surfaces on said spider and said member formed to permit relative movement of said spider and said member about an axis also parallel to said pivot. 100

5. A watch case vulcanizer comprising a pivotally supported movable mold section; mechanism for holding said movable section in position against a cooperating mold section comprising, a spider having its outer engaging surface arranged to bear against said movable section, and a bar pivotally supported for movement about an axis parallel to the pivot supporting said movable section, and arranged to engage said spider over cooperating surfaces on said spider and said bar formed to permit relative movement of said spider and said bar about an axis also parallel to said pivot; and means on said bar and said movable section formed to interengage upon outward movement of said bar to cause such movement to break said movable section from said cooperating section. 115 120 125 130

6. A watch case vulcanizer comprising a pivotally supported movable annular mold section; mechanism for holding said movable section in position against a cooperating mold section comprising, a spider having its outer engaging surface arranged to bear against said movable section along the entire circumference thereof, and a bar pivotally supported for movement about an axis parallel to the pivot supporting said movable section, and arranged to engage said spider over cooperating surfaces on said spider and said bar formed to permit relative movement of said spider and said bar about an axis also parallel to said pivot; and means on said bar and said movable section formed to interengage upon outward movement to break said movable section from said cooperating section.
- 10 7. A watch case vulcanizer comprising a pivotally supported movable mold section; and mechanism for holding said movable section in position against a cooperating mold section comprising, a spider having its outer engaging surface arranged to bear against said movable section and itself formed to then close the central opening in the outer face of said section, and a member pivotally supported for movement about an axis parallel to the pivot supporting said movable section, and arranged to engage said spider over cooperating surfaces on said spider and said member formed to permit relative movement of said spider and said member about an axis also parallel to said pivot.
- 15 8. A watch case vulcanizer comprising a pivotally supported movable annular mold section; and mechanism for holding said movable section in position against a cooperating mold section comprising, a spider having its outer engaging surface arranged to bear against said movable section along the entire circumference thereof and itself formed to then close the central opening in the outer face of said section, and a member pivotally supported for movement about an axis parallel to the pivot supporting said movable section, and arranged to engage said spider over cooperating surfaces on said spider and said member formed to permit relative movement of said spider and said member about an axis also parallel to said pivot.
- 20 9. A watch case vulcanizer comprising a movable annual mold section provided with a cavity for the reception of heating fluid; and separate mechanism for holding said movable section in position against a cooperating mold section comprising, a spider having its outer engaging surface arranged to bear against said movable section about the entire circumference of said movable section, and a member arranged to engage said spider to force said spider into tight engagement with said movable section and said movable section into tight engagement with such cooperating section.
- 25 10. A watch case vulcanizer comprising a movable annular mold section provided with a cavity for the reception of heating fluid; and separate mechanism for holding said movable section in position against a cooperating mold section comprising, a spider having its outer engaging surface arranged to bear against said movable section about the entire circumference of said movable section, and a member pivotally supported for movement about an axis parallel to the pivot supporting said movable section, and arranged to engage said spider, over cooperating surfaces on said spider and said member formed to permit relative movement of said spider and said member about an axis also parallel to said pivot, to force said spider into tight engagement with said movable section and said movable section into tight engagement with such cooperating section.
- 30 11. A watch case vulcanizer comprising a movable annual mold section provided with a cavity for the reception of heating fluid; and separate mechanism for holding said movable section in position against a cooperating mold section comprising, a spider arranged to close the central opening in the outer face of said movable section and having its outer engaging surface arranged to bear against said movable section about the entire circumference of said movable section, and a member arranged to engage said spider to force said spider into tight engagement with said movable section and said movable section into tight engagement with such cooperating section.
- 35 12. In testimony whereof I hereunto affix my signature.

LEGER S. CASTONGUAY.
